TABLE

William C. Andrus, Wyoming, Mich., assignor to Steelcase Inc., Grand Rapids, Mich.

Filed Mar. 27, 1972, Ser. No. 238,729

Term of patent 14 years

Int. Cl. D6—03

U.S. Cl. D6—27

FIG. 1.

FIG. 2.

FIG. 4.

FIG. 3.

FIG. 5.

FIG. 6.

FIG. 1 is a side elevational view of a table embodying my design, all sides being the same;

FIG. 2 is a top plan view of the table;

FIG. 3 is a bottom plan view of the table;

FIG. 4 is a perspective view of the table;

FIG. 5 is a side elevational view of an alternative embodiment table embodying my design, all side views being the same; and

FIG. 6 is a perspective view of the table of FIG. 5.

The top plan view and the bottom plan view of the alternative embodiment table shown in FIGS. 5 and 6 would be the same in proportion as FIGS. 2 and 3.

I claim:

The ornamental design for a table, substantially as shown and described.
